United States Patent Office.

ABNER BASSETT, OF VIRGINIA CITY, NEVADA.

Letters Patent No. 61,383, dated January 22, 1867.

IMPROVED APPARATUS FOR AMALGAMATING ORES.

The Schedule referred to in these Letters Patent and making part of the same.

TO ALL WHOM IT MAY CONCERN:

Be it known that I, ABNER BASSETT, of the city of Virginia, county of Storey, State of Nevada, have invented certain new and useful improvements in "Amalgamators" for working gold and silver-bearing ores and extracting the precious metals, called "Bassett's Amalgamator;" and I do hereby declare the following description and accompanying drawings are sufficient to enable any person skilled in the art or science to which it most nearly appertains, to make and use my said invention without further invention or experiment.

The nature of my invention consists of a barrel or other suitable vessel, with a hollow shaft passing longitudinally through the centre, by which heat is introduced by means of exhaust steam, or otherwise; the barrel or cylinder being inclosed in a shell or bath whereby hot air is introduced around the entire circumference of the barrel, as well as through the centre. The pulp not coming in contact with the steam, important chemical changes are effected by the heat in itself. In the drawings—

Figure 1 is a side elevation.

Figure 2, a longitudinal section.

Figure 3, a side view in segment.

a a a, stuffing-boxes; *b*, pulley by which the machine is driven; *c*, hollow-shaft, open at both ends, for introducing the steam pipes *d d'*, *d'* being the induction pipe, and *d* the escape pipe. *e* is a barrel or other shaped suitable vessel, constructed of iron or other suitable material, through which the hollow shaft *c* passes; the shaft being constructed tight, so as not to admit the steam or heat directly into the pulp or ore to be amalgamated, but imparts its influence upon the outer circumference of the barrel or vessel which contains the pulp. *f* is a man-hole of barrel; *g*, discharging pipe. The outside shell or bath, *h*, in which the barrel is revolved, is formed in halves, coupled together by means of flanches and bolts. *i i'* are steam pipes; *i* is the induction pipe, *i'* the escape pipe. *J J* are hatchways on the outside shell, used principally for testing and discharging the ore or pulp. The whole being mounted upon some suitable frame, the shell resting upon pins placed at suitable distances around the inside of the frame. By this arrangement it is not intended that the shell shall revolve, but remain stationary, enclosing the barrel through which the hollow shaft or cylinder passes, causing it to revolve by means of the pulley *b*. The ore to be amalgamated is placed in the barrel with the usual accompaniments well known to metallurgists, when the steam or heat is admitted through the hollow shaft, and into the shell through the pipe *i*, and the barrel slowly revolved until a complete amalgamation is effected. By this arrangement of introducing steam or heat, both on or through and around the pulp, without coming in direct contact with it, great beneficial chemical changes are produced, generating gases, and causing a separation of metals from obdurate ores, which is indispensable for a free amalgamation.

Having thus described my invention, I will now proceed to state what I claim, and desire to secure by Letters Patent; that is to say, I do not claim the use of steam for amalgamation of ore.

What I claim, is—

1. The barrel *e* or its equivalent, having a hollow shaft, *c*, passing through it, by which heat is introduced by exhaust steam or otherwise, substantially as described and for the purpose set forth.
2. I claim the hot-air shell or bath *g*, for the purpose of applying heat, by exhaust steam or otherwise, to the outside of the vessel containing the pulp, whereby obdurate ores are made to amalgamate more freely, substantially as described, and for the purpose specified.
3. I claim the application of steam or heat to the ore or pulp, both through and around it, without coming in direct contact with it; the said ore or pulp being confined in some suitable vessel, said vessel being enclosed in a shell or bath, for the purpose herein set forth.

In witness whereof I have hereunto set my hand and seal this 16th day of August, A. D. 1866.

ABNER BASSETT. [SEAL.]
